[57] **CLAIM**

The ornamental design for a remote control for a combined ceiling fan and light fixture, as shown and described.

DESCRIPTION

FIG. 1 is a front perspective view of a remote control for a combined ceiling fan and light fixture showing my new design;

FIG. 2 is a front elevational view thereof;

FIG. 3 is a right side elevational view thereof, the left side being a mirror image;

FIG. 4 is a bottom plan view thereof;

FIG. 5 is a top plan view thereof;

FIG. 6 is a rear elevational view thereof; and

FIG. 7 is a front perspective view showing a front door in a downward position.

FIG. 1

FIG. 3

FIG. 2

FIG. 4

FIG. 5

FIG. 6

FIG. 7
